SELF-FEEDING INKWELL

James L. Cunningham, Kansas City, Mo.

Application August 15, 1934, Serial No. 739,956

6 Claims. (Cl. 120—59)

My invention relates to a self-feeding ink-well in which an elevated reservoir is employed for automatically supplying the ink-well as the ink is used therefrom.

5 In carrying out the invention a duct is employed for connecting the ink-well with the reservoir so that the latter may be filled by tilting the entire device to an angle of about forty-five degrees and pouring ink into the ink-well. Said 10 duct also serves to conduct the ink from the reservoir back into the ink-well as needed when the device is in position for use.

An air tube connecting the ink-well to the reservoir is employed so that air within the latter may be readily displaced by the ink during 15 the filling operation.

The lid of the ink-well is provided at its underside with a channel so that when said lid is opened it constitutes a spout for conducting the 20 ink into the ink-well from a bottle or other container without wastage during the filling operation.

The device may be of plain or ornamental design as preferred.

25 Other features will hereinafter appear and in order that the invention may be readily understood reference will now be had to the accompanying drawings, in which:

Fig. 1 is a perspective view of the device with 30 the ink-wells removed from the base.

Fig. 2 is a fragmentary plan view of the base with one of the ink-wells in position therein.

Fig. 3 is an irregular vertical cross section on line 3—3 of Fig. 4, with the reservoir removed.

35 Fig. 4 is a vertical cross sectional view of the complete device.

In carrying out the invention I employ a hollow base 2 provided at its forward portion with a suitable number of grooves 4 for holding pencils, paper clips, pens, pins and the like.

40 6 designates one of the ink-wells, two of which are provided in the present instance, but since they are duplicates only one will be described in detail. The bottom 8 of the ink-well 6 slopes 45 downwardly and rearwardly towards the funnel-shaped rear portion 10 of said ink-well. The upper portion of the ink-well 6 is provided with a neck 12 which fits snugly within the respective opening 14 in the base 2. The neck 12 is 50 movably secured in the opening 14 by means of a shoulder 18 and an annular nut 20 which latter is threaded in said neck. The shoulder 18 abuts the underside of that portion of the base 2 surrounding the neck 12 and the nut 20 overlaps said base.

The upper portion of the ink-well 6 is provided with a close fitting lid 22 to reduce evaporation of the ink to a minimum. The lid 22 is operably connected to the rear portion of the nut 20 by a hinge 24 and provided at its under portion with a downwardly and rearwardly extending tongue 26 equipped with a catch 28 adapted to engage a lip 30 on the nut 20 and thus limit the opening movement of said lid as shown by dotted lines, Fig. 4. The front portion of the lid 22 has a cavity 32 for insertion of the thumb whereby the lid may be raised to the open position disclosed by dotted lines, Fig. 4. A channel 36 is formed in the underside of the tongue 26 and extends substantially the entire length 10 thereof. The sides of the tongue 26 and the channel 36 diverge towards their forward ends, 15 Figs. 2 and 3, to provide a wide portion for the reception of the mouth of a bottle or other ink container during the operation of filling a reservoir 40. 20

The reservoir 40 is mounted upon the rear portion of the base 2 to which it is removably secured by suitable means such as studs 42 and nuts 44. Communication between the ink-well 25 6 and the reservoir 40 is established by suitable means such as a duct 46 leading from the bottom of the reservoir 40 to the funnel-shaped rear portion 10 of the ink-well. Communication is also established by means of an air tube 48 leading from a point near the bottom of the ink-well 30 to the upper inner portion of the reservoir 40.

In practice the reservoir 40 may be supplied with ink by first raising the lid 22 to the dotted line position, Fig. 4, and then tilting the entire 35 device backwardly at an angle of about forty-five degrees. The mouth of a bottle or other ink container is applied to the wide upper portion of the channel 36 and the container is then tilted until sufficient ink flows down said channel 40 36 and through the ink-well to fill the reservoir 40 to the desired depth. The channel 36 and the funnel-shaped rear portion 10 of the ink-well cooperate in directing the ink to the reservoir 40, so that there is no danger of wastage if reasonable care is exercised during the filling operation. As the ink flows into the reservoir 40 it displaces the air therein which escapes through the air tube 48. When the device is restored to normal position, that is with its base 2 in a 45 horizontal plane, ink flows from the reservoir 48 through the duct 46 into the ink-well 6 until the lower ends of the duct 46 and the air tube 48 are submerged. When this occurs the flow of ink from the reservoir 40 is checked until enough 50 55

ink has been used from the ink-well to partially uncover the lower end of the duct 46, whereupon the ink again flows from the reservoir until the lower end of the duct becomes submerged. 5 From the foregoing it will be understood that as ink is used from time to time the level in the ink-well will be automatically restored to normal with ink flowing from the reservoir through the duct 46.

10 While I have shown the device arranged for two ink-wells, it is to be understood that a greater or less number may be employed by forming the base 2 accordingly.

15 From the foregoing description it is apparent that I have provided a device which is well adapted for the purpose intended, and while I have shown one embodiment of the invention I reserve all rights to such other forms and modifications thereof as properly fall within the 20 spirit and scope of the invention as claimed.

Having thus described my invention, what I claim and desire to secure by Letters Patent, is:

1. A device of the character described comprising a base having an opening therein, an ink-well located within said opening, a lid operably mounted upon said ink-well and provided at its underside with a channel extending to the rear margin of the lid and adapted to direct ink into the ink-well when the latter is tilted rearwardly and the lid is opened, a reservoir mounted upon said base, and a duct connecting the ink-well and said reservoir. 30

2. A device of the character described comprising a base having an opening therein, an ink-well having a neck snugly fitting within said opening, a shoulder on said ink-well for engagement with the underside of that portion of the base surrounding the opening, an annular nut 35 threaded on the neck and overlapping the upper

side of the base, a lid for the ink-well hinged to said nut, a catch on the underside of the lid, a lip on the nut in the path of said catch to limit the opening movement of the lid, a reservoir mounted upon said base, and a duct connecting the ink-well and said reservoir. 5

3. A device of the character described comprising a base, an ink-well supported by said base and provided with a funnel-shaped rear portion, a lid operably mounted upon said ink-well and provided at its underside with a channel extending towards said funnel-shaped rear portion and adapted to direct ink to the latter when said lid is opened and the ink-well is tilted rearwardly, a reservoir mounted upon said base, and a duct connecting the funnel-shaped rear portion of the ink-well and said reservoir. 10 15

4. In a device of the character described, an ink-well, a hinged lid for said ink-well, a tongue on the underside of said lid extending rearward and terminating in a catch, and means for coacting with said catch in limiting the opening movement of the lid. 20

5. In a device of the character described, an ink-well, a hinged lid for said ink-well, a tongue on the underside of said lid extending rearward and terminating in a catch, said tongue having a longitudinal channel therein, means for coacting with said catch in limiting the opening movement of the lid, and a reservoir communicating 30 with the ink-well to supply the same with ink. 25

6. In a device of the character described, an ink-well, an annular nut removably engaging the upper portion of said ink-well, a lid for the ink-well hinged to said nut, a catch on said lid, and a lip on the nut arranged in the path of said catch to limit the opening movement of the lid. 35

JAMES L. CUNNINGHAM.
